UNITED STATES PATENT OFFICE.

ERNEST JOSEPH WASBROOD, OF MONTREAL, CANADA.

CASTER-SOCKET.

SPECIFICATION forming part of Letters Patent No. 685,073, dated October 22, 1901.

Application filed March 18, 1901. Serial No. 51,664. (No model.)

To all whom it may concern:

Be it known that I, ERNEST JOSEPH WASBROOD, of the city of Montreal, in the district of Montreal and Province of Quebec, Canada, 5 have invented certain new and useful Improvements in Caster-Sockets; and I do hereby declare that the following is a full, clear, and exact description of the same.

My invention has for its object to provide 10 a holder which will serve the double purpose of yieldingly retaining itself and the caster independently against displacement while in use and at the same time to provide a simple, inexpensive, and durable socket.

15 To this end the invention may be said briefly to consist in constructing a caster-socket from a single strip of metal bent to form top and bottom bracing cross-pieces and resilient sides. This frame in the fully-developed embodiment of my invention is constructed from a single piece of metal comprising top and bottom cross-pieces and side pieces and a pair of resilient wings to bear upon the interior of the opening in the end 25 of the bedstead or other leg, while the end pieces of the frame have a tube set therein with a resilient catch to hold the caster, and a washer is formed to set within the frame and be held and carried thereby.

30 For full comprehension, however, of my invention reference must be had to the accompanying drawings, forming a part of this specification, in which like symbols indicate the same parts, and wherein—

35 Figure 1 is a side elevation of my improved socket with a caster in place. Fig. 2 is also a side elevation thereof, but the view is taken at right angles to the direction from which Fig. 1 is taken. Fig. 3 is a top view of the socket 40 with caster in place and with the resilient parts for retaining the caster sprung open to release it. Fig. 4 is a detail view of the strip from which the socket-frame is bent. Fig. 5 is a detail view of the tube for receiving the 45 caster-spindle. Fig. 6 is a detail view of the washer, and Fig. 7 is a perspective view of my frame alone without its auxiliary resilient retaining devices.

The frame of my improved socket consists 50 of a metallic strip bent to form the bottom cross-piece *b*, top cross-piece *c*, side pieces *d* and *d'*, and resilient wings *e*, integral with the top cross-piece *c*, each of the said top and

bottom cross-pieces having openings therein, and the abutting ends of the side piece *d* and 55 bottom cross-piece are formed, respectively, with a tongue *f* and notch *g*, which interlock with one another.

A tube *h* has its lower end set in the opening in the bottom cross-piece and projecting 60 slightly therethrough, said lower end being spun, as at *i*, over the edge of said opening to secure it rigidly in place. The upper end of this tube projects a short distance through the opening in the top cross-piece and is slot- 65 ted, as at *j*, to form resilient fingers *k*, while the edge of the opening in said top cross-piece is provided with a series of inwardly-projecting teats *l*, which take into the slots *j* and serve the double purpose of securing the tube 70 against longitudinal displacement and of relieving the resilient fingers *i* of the lateral pressure of the caster-spindle *m*.

The washer, which is set in place before the tube, consists of a disk *n*, centrally perforated, as at *o*, and cut away at diametrically opposite sides, as at *p*, to straddle the side pieces *d* and *d'* of the frame. 75

When my improved socket is set in place in the usual opening in the bedstead or other leg, the resilient wings *e* and the sides *d* will bear upon the walls of said opening and retain the socket against displacement, and when the spindle *m* of the caster is thrust home the knob or head *g* thereof will force the resilient fingers apart and pass them and when the bedstead is lifted will be supported on the tops thereof. 85

If desired to supply the demand for an inexpensive and simple socket, the frame alone 90 can be used, as shown in Fig. 7, without the tube and resilient wings and with or without the washer. In such a case the resilient sides alone will retain the socket against displacement, while of course if the article of furniture which the caster supports is lifted said 95 caster will fall from place.

What I claim is as follows:

1. A caster-socket blank consisting of a strip of metal having two straight portions 100 constituting the sides of the socket and of even width throughout their length; a perforated portion between and of greater width than said straight portions; a perforated portion at the end of one of the straight portions; 105 and the opposite ends of said blank being

formed respectively with a notch and tongue, substantially as described.

2. A caster - socket made from a single length of metal and consisting of top and bottom perforated cross - pieces, and resilient side pieces, said top cross - piece being integral with one end of each of said resilient side pieces, and one side edge of said bottom cross - piece being integral with the opposite end of one of said resilient side pieces; the free end of the other side piece terminating at the adjacent free edge of the bottom cross - piece; and means limiting the movement of the end of said free side piece toward the other side piece substantially as described and for the purpose set forth.

3. A caster - socket made from a single length of metal and consisting of top and bottom perforated cross - pieces and resilient side pieces, said top cross - piece being integral with one end of each of said resilient side pieces, one side edge of said bottom cross - piece being integral with the opposite end of one of said resilient side pieces, the opposite side edge of said bottom cross - piece being slotted and the free end of the other resilient side piece being formed with a lug substantially as described and for the purpose set forth.

4. A caster - socket made from a single length of metal and consisting of top and bottom perforated cross - pieces, resilient side pieces and laterally-bearing resilient wings in one piece with said top cross - piece, substantially as described and for the purpose set forth.

5. A caster - socket made from a single length of metal and consisting of top and bottom perforated cross - pieces, resilient side pieces and laterally-bearing resilient wings in one piece with diametrically opposite sides of said top cross - piece, substantially as described and for the purpose set forth.

6. A caster - socket made from a single length of metal and consisting of top and bottom perforated cross - pieces, resilient side pieces and laterally-bearing resilient wings in one piece with diametrically opposite sides of said top cross - piece, said top cross - piece being integral with one end of each of said resilient side pieces, and one side edge of said bottom cross - piece being integral with the opposite end of one of said resilient side pieces, substantially as described and for the purpose set forth.

55 7. A caster - socket made from a single length of metal and consisting of top and bottom perforated cross - pieces, resilient side pieces and laterally-bearing resilient wings integral with diametrically opposite sides of said top cross - piece, said top cross - piece being integral with one end of each of said resilient side pieces, one side edge of said bottom cross - piece being integral with the opposite end of one of said resilient side pieces,

60 65 the opposite side edge of said bottom cross - piece being slotted and the free end of the other resilient side piece being formed with a

tongue, substantially as described and for the purpose set forth.

8. A caster - socket made from a single length of metal and consisting of top and bottom perforated cross - pieces, and resilient side pieces, the top cross - piece having a series of teats projecting into the perforation therein, and a tube having resilient fingers at its upper end, said tube being rigidly connected at its lower end to the edge of the perforation in the bottom cross - piece and having its upper end projecting a short distance through the perforation in the top cross - piece, with said teats projecting between said resilient fingers, substantially as described and for the purpose set forth.

9. A caster - socket made from a single length of metal and consisting of top and bottom perforated cross - pieces, resilient side pieces, and laterally-bearing resilient wings integral with diametrically opposite sides of said top cross - piece, said top cross - piece being integral with one end of each of said resilient side pieces, one side edge of said bottom cross - piece being integral with the opposite end of one of said resilient side pieces, the opposite side edge of said bottom cross - piece being slotted and the free end of the other resilient side piece being formed with a tongue, the top cross - piece having a series of teats projecting into the perforation therein, and a tube having resilient fingers at its upper end, said tube being rigidly connected at its lower end to the edge of the perforation in the bottom cross - piece and having its upper end projecting a short distance through the perforation in the top cross - piece, with said teats projecting between said resilient fingers.

10. The combination with a caster - socket consisting of perforated top and bottom cross - pieces and a pair of side pieces, of a washer located between said side pieces and supported upon said bottom cross - piece and having two of the opposite sides thereof cut away to straddle said side pieces, substantially as described and for the purpose set forth.

11. A caster - socket made from a single length of metal and consisting of top and bottom perforated cross - pieces, and resilient side pieces, said top cross - piece being integral with one end of each of said resilient side pieces, one side edge of said bottom cross - piece being integral with the opposite end of one of said resilient side pieces, and a washer located between said side pieces and supported upon said bottom cross - piece and having two of the opposite sides thereof cut away to straddle said side piece, substantially as described and for the purpose set forth.

In testimony whereof I have affixed my signature in presence of two witnesses.

ERNEST JOSEPH WASBROOD.
